UNITED STATES PATENT OFFICE.

HARRY G. OSBURN, OF PITTSBURGH, PENNSYLVANIA.

IGNITING SYSTEM.

1,126,266.

Specification of Letters Patent. Patented Jan. 26, 1915.

Application filed May 22, 1911. Serial No. 628,722.

To all whom it may concern:

Be it known that I, HARRY G. OSBURN, a citizen of the United States of America, residing at Pittsburgh, in the county of Allegheny and State of Pennsylvania, have invented certain new and useful Improvements in Igniting Systems, of which the following is a specification, reference being had therein to the accompanying drawings.

10 This invention relates to igniting systems for gas engines, and it has for one of its objects the provision of dual means for creating a spark, and comprising in effect a pair of complete ignition-outfits, either of 15 which may be utilized without affecting the other.

The invention has furthermore, for its object the provision of a pair of different apparatus, one of which complements the 20 other in its initial or starting operation, after which the second apparatus may be used to better advantage and to the exclusion of the first.

The invention has furthermore for its object 25 the improved organization of some of the co-operative elements into substantially a single unit which may be removed bodily for repairs and requires the disconnection of very few electrical connections without in 30 any way interfering with the operation of the other set.

A further object of the invention resides in the provision of a circuit breaker whereby either one or the other ignition apparatus 35 may be brought into action.

Other objects of the invention will herein-after appear and be defined in the claims.

The invention has been clearly illustrated in the accompanying drawings, in which 40 similar characters denote similar parts, and in which—

Figure 1 is a side view of the magneto and its driving mechanism and connections with the other elements of my improved system; 45 Fig. 2 is a top view of the magneto-driver and the base upon which the magneto is normally seated, *per se*; Fig. 3 illustrates in two face-views and one edge-view, the coupling member employed between the magneto and its driver.

Briefly stated, my improved system comprises, (in connection with the spark-plugs of an engine, the distributing and timing mechanisms therefor and the spark-coil,) a magneto circuit and also a battery-circuit, 55 either circuit being adapted to be thrown into connection with the permanent elements just mentioned, by a two-point switch. The battery circuit has its own condenser; so has the magneto-circuit, the magneto and its condenser being so organized that mechanically they constitute one single machine-unit which may be readily removed from its supporting base which also carries the timing and distributing devices, and also 60 the driving shaft whereby all of these three members just mentioned are operated.

Referring now to the drawings, (Fig. 1) the engine comprises four cylinders having spark-plugs P^1 , P^2 , P^3 , P^4 , separately connected by conductors with four terminals d^1 , d^2 , d^3 , d^4 , of a distributor mechanism D which comprises the usual revoluble arm actuated in a positive manner from the engine-shaft 10 by any suitable means (not 70 shown), through the intervention of a vertical spindle 11 (see Fig. 2). This spindle is electrically connected at its top through a conductor 12 with the outer winding of an induction coil I, and thence by wires 13, 14, 80 15 to the metallic frame of the engine where it is "grounded" into electrical connection with the bodies of the several spark plugs. The circuit just described constitutes the "secondary" circuit established by either 85 one or the other of a pair of primary circuits including a magneto and a battery respectively.

In order to start the engine, the battery-circuit is generally used, after which the 90 battery-current is cut-out, and the magneto current is cut-in on account of its constancy and economy in operation.

Referring now, first to the "battery-circuit", the battery B is connected with one 95 pole 16 of a switch S, the arm 17 of which is permanently connected by a conductor 18 with one end of the inner winding of the coil I. The battery-circuit is completed through the conductor 13 above mentioned, 100

- and through a breaker arm V which is preferably positively operated by a multi-rise cam 19 on the spindle 11, and which makes and breaks contact with a terminal 20, the latter being connected with the other pole of the battery, by a conductor 21. In order to protect the contact points 20, the two elements of a condenser C are connected with the conductor 13 and 21 respectively.
- 10 In regard to the "magneto circuit" it will be noted that the latter includes the conductor 18 above mentioned, as well as the inner winding of the induction coil I, then the conductor 13, and then a breaker arm v' also operated in a positive manner, as by a multi-rise cam 19' on the same spindle 11. The arm v' makes and breaks contact with a terminal 25 which connects by conductors 26, 26' with one pole 27 of the magneto M, while the other pole 28 thereof leads through a conductor 29 to the second pole 30 of the two-point switch S, the circuit being then closed by the movement of the arm 17 into position shown by dotted lines in Fig. 1, this movement resulting in opening the battery-circuit. In order to protect the contact point 25, a condenser C' is placed in communication with the point 25, through the conductor 26 above mentioned, and the wire 31, the other element of the condenser C' being connected by metallic elements, and the conductor 14 with the breaker arm v'.
- Now, inasmuch as the condenser C pertains to the magneto M exclusively, both of these devices are secured together to constitute a machine-unit which requires the disconnection of only two terminals in order to permit the same to be removed from all the other elements of the system, and without 40 in any way disturbing the operativeness of the battery-circuit, these two terminals being those designated by the numerals 25 and 28 above named, (see also Figs. 1 and 2). Both of the breaker cams, and their arms v, v' are disposed in a casing 35 of a timing mechanism and surrounding the spindle 11 at that point, the particular construction and movement of this casing being neither shown or described herein as it does not 50 form any part of the present invention except in a generic sense. Since the shaft 10 is operated in a fixed ratio to the engine-shaft, and since furthermore the spindle 11 carries the distributor around, the former is 55 actuated so as to synchronize with the engine shaft, and means are also provided for detachably connecting the shaft 10 with the armature shaft m (see Fig. 1) of the magneto M.
- 60 In the present instance the magneto has a base plate 40 provided with a cylindrical boss 41 which is adapted to be seated in the cylindrical aperture 42 of a platen 43, upon

which the housing for the spindle 11 is also secured, the aperture 42 being in direct longitudinal alignment with the axis of the shaft 10. The magneto is thus accurately positioned on the platen, and it is preferably secured in place by set-screws 44, (see Figs. 1 and 2).

The driving shaft 10 and the armature shaft m are coupled by a member 45 interposed between and in engagement with, both of them, without requiring any fastening means. For the purpose of causing both of the shafts to rotate simultaneously, the disk-coupling 45 is provided at opposite sides thereof with diagonal ribs 47, 48, disposed substantially at right angles to each other and adapted to enter grooves provided therefor in the adjacent ends of the armature-shaft and driving shaft, respectively. By virtue of this slip construction the coupling is in reality an elastic one, and in order to disassemble the magneto from the shaft 10, it must first be lifted bodily until its boss 40 is clear of the platen as shown in Fig. 1, it being understood that one set of ribs 47, 48 must be in vertical position to permit this rising movement, after which the magneto, in its entirety and together with the condenser is free to be carried away for repairs without requiring any disconnections of parts other than of those above stated.

I claim:—

1. In a dual igniting system for engines comprising a battery, a magneto, two circuit breakers, an induction coil and a two-point switch, the combination of the two circuit breakers having their movable contacts in electric connection with one terminal of the primary of said coil, the two-point switch having its movable contacts in electrical connection with the other terminal of said primary coil and its fixed contacts in electric connection with the fixed contacts of the circuit breakers respectively, the battery being in one and the magneto in the other one of said connections, a drive connection between the engine and the circuit breakers and a separable drive connection between the engine and the magneto, said magneto forming a removable unit of the system.

2. In a dual igniting system comprising a battery, a magneto, two circuit breakers, two condensers, an induction coil and a two-point switch, the combination with a base plate upon which the circuit breakers and their actuating mechanism are mounted, detachable connection between the magneto and said base plate and between it and the actuating mechanism of the circuit breakers, a battery circuit including one of the circuit breakers, the primary of the induc-

tion coil, the movable contact of the two point switch and one of the fixed contacts thereof, a magneto circuit including the remaining circuit breaker, the primary of the 5 induction coil, the movable contact of the two point switch and the remaining fixed contact thereof, the magneto being detachably connected in said circuit and forming

with its condenser an independent removable unit of the system.

In testimony whereof I affix my signature in presence of two witnesses.

HARRY G. OSBURN.
